FIG. I.

Des. 198,796

PAGE 2

FIG. 2.

FIG. 3.

FIG. 4.

FIG. 1 is a perspective view of a dresser, showing my new design;

FIG. 2 is a front elevational view thereof;

FIG. 3 is a top view; and

FIG. 4 is a side elevational view of the same.

The back of the article is plain and unornamented. The dominant features of my design reside in those portions shown in full lines on the drawing.

This application is a division of my application Serial No. D. 72,612, filed November 27, 1962, now abandoned.

I claim:

The ornamental design for a dresser, as shown and described.
